UNITED STATES PATENT OFFICE

2,524,917

PAPER-CUTTING MACHINE

Victor Z. Lynnequest, Omaha, Nebr.

Application March 3, 1947, Serial No. 732,059

4 Claims. (Cl. 164—54)

1

The present invention relates to the art of cutting stacks of paper and more particularly to a power driven paper cutting machine.

It is an object of the invention to provide a device which compacts a stack of paper to be cut and locks the stack in a manner preventing movement and slightly in advance of the descending motion of a cutter or knife which severs the stack into two parts.

As heretofore practiced in the art, paper cutters have been provided with a manually actuated frame screw having a heavy wheel on the upper end thereof, whereby the operator would at first spin and then later twist the wheel for causing a bar to descend for locking a stack of paper upon the cutting table. The operator after locking the stack in this manner, then manipulates a knife attached to the machine of the prior art, whereby the entire operation has heretofore been time consuming and with an excessive attendant labor cost.

Attempts have been made to automatically do these operations and machines have been provided and employed for severing stacks of paper by the employment of a power actuated knife as well as power locking mechanisms for locking a stack of paper prior to a severance thereof. These machines have been so constructed that they employ leather gaskets operating on a horizontally disposed shaft to actuate the clamp bar which locks the stack of paper. A difficulty with this form of mechanism is that the leather gaskets become impregnated with oil to such an extent that they bind upon the slidable bar and lock the bar against the desired motion, whereupon the bar or other parts of the mechanism frequently break, and it is therefore an object of the invention to provide a mechanism which obviates the undesirable features of the prior practice.

Another object of the invention is to provide a mechanism which consummates the locking and cutting of the paper automatically and by the use of power, whereby labor cost is minimized.

Still another object of the invention is to provide a paper cutter having a paper clamping bar which is power operated for producing a clamping effect greater than that caused by the weight of the clamping bar alone.

A further object of the invention is to provide a paper cutter as described employing a clutch particularly useful for applying power to said clamping bar.

A still further object of the invention resides in the provision of a clutch for many other uses

2

in which uses it is desired to exert a pulling force through the two sections of a clutch in one direction, at times, and have a freedom of movement of the sections of the clutch toward each other at other times.

Other and still further objects and advantages of the invention will become apparent from the following description of a preferred embodiment thereof.

10 In the drawings:

Figure 1 is a frontal elevation of the paper cutter of the invention, certain parts thereof being broken away;

15 Figure 2 is a left end elevation of the device of Figure 1, an extra spring mechanism employed not being shown;

Figure 3 is a view in section taken along the line 3—3 of Figure 1;

20 Figure 4 is a detailed rear elevation of the upper section of the paper cutter, certain parts thereof being broken away;

Figure 5 is a view in section taken along the line 5—5 of Figure 4;

25 Figure 6 is a detailed left-end view of the clutch mechanism employed;

Figure 7 is a view in section taken along the line 7—7 of Figure 8;

Figure 8 is a view in section of the clutch mechanism taken looking downwardly between the lines 8—8 and the line 9—9 of Figure 6; and

30 Figure 9 is a detailed top plan view of an annular spring-engaging member employed in the invention.

The paper cutting machine of this invention includes a table-top 10 for receiving and upholding paper to be cut, which latter is placed at 12. The table-top 10 is preferably oblong and is supported by four legs 14.

Above each of the ends of the table-top 10 are 40 a pair of guide-standards 16, each standard of a pair being spaced apart sufficiently for slidably receiving therebetween a cutting blade 18. The respective pairs of guide-standards 16 are interconnected at their upper ends by a brace 20.

45 The cutting blade 18 extends the length of the table 10 and is securely held in a blade-holder 22 by means of a series of bolts 24. The blade holder 22 is provided with a notch 26 for receiving the blade 18 as best shown in Figure 5, and is further provided with reinforcing ridges 28 extending transversely and longitudinally thereof.

At one end the blade holder 22 is supported by a pivotally mounted bracket arm 29, the arm being attached to the holder 22 by a pin 30 and 50 to the brace 20 by a pin 32 so that the holder

22 may swing downwardly and in a direction toward the standard 16 adjacent the bracket arm 29.

The other end of the blade holder 22 is pivotally supported by a pin 34 in the lower corner of an equalizing lever 36, the latter being triangular and pivotally secured by another pin 38 to the brace 20 and by a third pin 40 to a knife bar pull rod 42. The triangular equalizing lever 36 is so shaped that the pins 38 and 40 are at either side and above the pivot pin 34.

The knife bar pull rod 42 is eccentrically and pivotally secured to a small wheel 44 as by means of the crank pin 46. The wheel 44 is in turn mounted and keyed to a drive shaft 48, the latter being mounted on suitable framework 49, the latter being preferably secured to the table-legs 14 and the table-top 10. Also keyed to the drive shaft 48 is a large pinion 50 of greater circumference than the wheel 44; and the large pinion 50 is driven by a smaller pinion 52.

The smaller pinion 52 is splined to a shaft 54, and the latter is driven by a motor, not shown. Assuming that the motor speed is 1700 R. P. M., the said speed is preferably reduced approximately in the ratio of six to one and the pinion 50 is then of a size for rotating one-sixth as fast as the small pinion 52.

The large pinion 50 is provided with a cam 56 of approximately triangular shape, the cam 56 being affixed to the forward side of the pinion 54. A rock lever 58 is positioned about and extending over the cam 56, one end of the rock lever 58 being pivotally secured, as at 60, to the framework 49.

The rock lever 58 is provided with a rotatably mounted roller 62 mounted thereon in a position for engaging the cam 56. The opposite end of the lever 58 from the pin 60 is connected to an upstanding clamp bar pull rod 64.

The clamp bar pull rod 64 is pivotally attached at its upper end to the forward end of a crank arm 66, the rearward end of the latter being secured to a clamp bar shaft 68. The clamp bar shaft 68 is of a length for overlapping the table 10 at each end and the shaft 68 is rotatably held by a pair of mounting brackets 70, the latter each being respectively secured to one of a pair of upright standards 16.

A clamping bar 72 is provided for compressing paper against the table top 12, the bar 72 being preferably heavily constructed, wide and flat at its lower end for engaging paper over a wide area. The clamping bar 72 is reinforced by ribs 74 extending both longitudinally and transversely thereof.

The clamping bar 72 is attached to the shaft 68 by means including a pair of vertical legs 76 at opposite ends of the bar 72, each of the legs 76 being pivotally secured at its lower end to a pair of apertured ears 77 by means of a pair of pins 78 and 79.

A second pair of legs 80 having their forward ends bifurcated are each pivotally secured to one of the vertical legs 76 by a pin 82. A pair of collars 84 are attached to the rearward ends of the second legs 80; and the collars 84 surround the shaft 68. A pair of set screws 86, extending through the respective collars 84 are for rigidly securing the collars 84 to the shaft 68.

In operation, at times when the above described mechanism is in the position shown in Figure 1, the knife blade 18 and the clamping bar 72 are in an up position. Paper, not shown, is then stacked

in the open space 12 on the table top 10, the selected place on the paper desired to be cut is placed under and in the path of the knife blade 18.

With the rotation of the motor driven pinion 50 in the direction of the arrow 87, the cam 56 will pass by the roller 62, permitting the rock lever 58 and the clamping bar 72 to descend under the influence of gravity. The weight of the clamping bar will then hold the paper in position. If desired, and where necessary, additional mechanism, to be later described, may be employed to further urge the clamping bar against the paper with a force in addition to that force caused by the weight of the bar 72.

As the pinion 50 and the wheel 44 continue their rotation, the pin 46 will pass by a point vertically above the shaft 48 following the passage of the cam 56, past the same point, the cam 56 being to the left of the pin 46 as seen in Figure 1.

The pin 46 will then begin to descend causing the knife blade 18 to define a slicing motion downward and to the right pivoting about the pins 32 and 38, as indicated by the arrows 88. The knife 18 will then slice the paper held by the clamping bar 72.

As the pinion 50 and wheel 44 continue rotation in the direction of the arrow 87, the cam 46 will again raise the clamping bar 72 and knife blade 18 and paper may be again inserted at 12, and the clamping bar and knife will again descend. Such a cycle will continue throughout operation.

When desired or found necessary, additional mechanism may be used to exert a downward force on the clamping bar 72.

Such mechanism preferably includes a second crank arm 90 rigidly secured at its rearward end to the opposite end of the shaft 68 from the first crank arm 66. The forward end of the crank arm 90 is pivotally secured by means of a pin 92 to the upper end of a collar member 94, the latter having a downwardly extending portion to opposite sides of which a pair of flat bars 96 are pivotally secured by means of a pin 98.

The flat bars 96 are maintained spaced apart by the collar member 94 for a purpose later described, and the bars 96 together form what will be termed an elongated member generally designated by the numeral 100 as best seen in Figure 6.

A clutching mechanism is employed for grasping and later releasing the bars 96. Such mechanism includes a yoke, the latter including a pair of yoke-plates 102 at opposite edges of the bars 96 and overlapping the bars 96. The yoke further includes a central bearing plate 104 extending between the bars 96, the bearing plate 104 being rigidly secured to the yoke-plates 102 by means of a pair of suitable pins 106.

The yoke-plates 102 are attached by means of a bolt 105 to a spring 107 and the latter is secured to the framework members 16 by any suitable means such as the hook 108, as best shown in Figure 1.

A pair of lever arms are positioned at opposite sides of the bars 96, the lever arms each being in two parallel arm-portions 110, the latter being spaced apart at their outer ends by a pair of cylindrical washers 112, the washers 112 each being held in place by a bolt 114. The lever arm portions 110 have smooth convex arcuate inner ends and are pivotally secured to the yoke-plates 102 at points between the respective ends of the lever arm-portions 110 by means of a pair of pins 116.

The inner ends of each pair of parallel arm-portions 110 are secured to one of a pair of con-

necting plates 118 by means of the pins 120, as best shown in Figure 8. Each of the connecting plates 118 are secured to a bearing plate 122, the latter being vertically disposed parallel to the connecting plates 118 for engaging and applying pressure on the flat bars 96. Bolts 124 are used to secure the connecting plates 118 to the bearing plates 122, the bolts 124 being threadedly received in apertures in the plates 122.

A pair of channel-bars 128 are respectively rigidly secured, one each, to the cylindrical washers 112 and the bars 128 extend downwardly converging toward each other and are attached at their lower ends to a ring 130. The ring 130 is constructed in two semi-circular parts attached together by means of bolts 132 thrust through pairs of outwardly flanged parallel ears 134, said ears being positioned on each end of the semi-circular portions of the ring 130.

A length of pipe 136 of a diameter for being slidably snugly received in the ring 130 is disposed in a vertical position between the bars 128. The top of the pipe 136 is provided with and attached to an annular member 138, having a circular center 140 and oppositely disposed arms 142 extending therefrom of a length for being slidably received in and guided by the channel bars 128. A compression spring 144 is disposed for bearing against the ring 130 at its lower end and the annular member 138 at its upper end. The spring is disposed coiled about the pipe 136, and the latter is disposed surrounding the lower ends of the flat bars 96.

The lower end of the pipe 136 is threaded for receiving a pair of large circular nuts 146, the latter being locked against each other in desired positions. At minimum compression, the spring 144 is of a length for permitting the nuts 146 to be disposed away from the ring 130 a distance sufficient for receiving an end of a horizontally disposed lever 148.

The lever 148 is pivoted at its other end to the framework 49 by means of a pivot pin 150. The lever 148 is actuated by a cam lever 152, the latter having a rounded lower end for the purpose of engaging a roller 154 which latter is rotatably secured to the center of the lever 148 by a bolt 156.

The cam lever 152 is pivotally mounted by a bolt 158, below the center of the lever 152. The upper end of the cam lever 152 is pivotally secured by a bolt 160 to one end of a reach rod 162, the other end of the latter being eccentrically pivotally connected to the small wheel 44.

In operation, the paper cutting machine of this invention functions in the following sequence. First, the power driving means is turned on to actuate the small driving pinion 52 which, in turn, drives the large pinion 50, the shaft 48 and the small wheel 44.

As the large pinion 50 rotates the cam 56 will raise the rock lever 58 and the clamping bar 72. Paper may then be inserted on the table 10 beneath the blade 18, in a desired cutting position.

As the cam 56 passes, the rock lever 58 and the clamping bar 72 will drop, holding the paper to the table 10. Following this, the small wheel 44 will move the reach rod 162 and the cam lever 158 into the dotted line position shown in Figure 1. The lever 148 will then push downwardly on the nuts 146 causing the pipe 136 and the attached annular member 138 to compress the spring 144 against the ring 130.

The channel bars 128 will then draw downwardly on the outer ends of the lever arms 110.

The yoke plates 102 and the arms 110 will tend to slide downwardly of the flat bars 96 and this tendency will be arrested by the spring 107. The lever arms 110 will then cause the bearing plates 122 to tightly engage and grasp the smooth flat bars 96, pushing the latter against the central bearing plate 104. The clutching mechanism will then be in an engaged position.

Continued pressure of the lever 148 will pull downwardly on the second crank arm 90 causing the clamping bar to apply further pressure on the paper. When the lever 148 has reached its lowest position, the wheel 44 will have turned to an extent for starting the slicing motion of the blade 18 in the direction of the arrows 33.

After slicing the paper, the continued rotation of the pinion 50 and the wheel 44 will cause the reverse of the above sequence replacing the parts in their original position for repetition of the above described operation.

If desired, and at times when an extra large stack of paper is to be cut, extra pressure, in addition to that applied to the paper as described, may be employed through the use of an additional spring mechanism.

Such an additional spring 166 may be employed, coiled about a vertically disposed rod 168. The lower end of the rod 168 is attached to a slide 170 which latter is for the purpose of bearing against and compressing the spring 166.

The upper end of the rod 168 is pivotally secured to the extended inner end of the pin 92. The rod 168 passes through an aperture in the central and upper portion of a U-shaped member 172, the lower ends of the latter being suitably secured to the free end of the lever bar 148.

In operation, at times when the lever 148 is in a downward position, the spring 166 will exert a pressure on the crank arm 90 and the clamping bar 72 in addition to the pull exerted by the spring 144. The pull of spring 144 is exerted by the free end of lever 148, when it is depressed by 152, and as 172 is attached to 148 it is lowered and compresses the spring against slide 170 which is integral with or attached to 168 and thus the lever 148 is raised to an "up" position when the spring in its compressed state lowers 170 and 168.

From the foregoing description, it is thought to be obvious that a paper cutting machine constructed in accordance with my invention is particularly well adapted for use by reason of the convenience and facility with which it may be assembled and operated, and it will also be obvious that my invention is susceptible of some change and modification without departing from the principles and spirit thereof and for this reason, I do not wish to be understood as limiting myself to the precise arrangement and formation of the several parts herein shown in carrying out my invention in practice, except as claimed.

I claim:

1. A paper cutting machine comprising a framework for supporting paper to be cut; a cutting blade slidably received by said framework; power actuated means attached to said cutting blade for causing said blade to define cutting movements; a clamping bar slidably received by said framework in a manner permitting the descent of said bar under the influence of gravity; means for alternately upholding and releasing said clamping bar; an elongated member attached to said clamping bar in a manner whereby said elongated member moves upwardly and downwardly simultaneously with said bar,

said elongated member having smooth longitudinal surfaces along at least a portion of its length; a clutching mechanism for grasping said smooth surfaces of elongated member at times when said member is in a downward position and releasing said member at times when said member is moving upwardly; and other power actuated means attached to said clutching mechanism for exerting a downward force on said clutch and said clamping bar in addition to the force of gravity.

2. A paper cutting machine comprising a framework for supporting paper to be cut; a cutting blade slidably received by said framework; power actuated means attached to said cutting blade for causing said blade to define cutting movements; a clamping bar slidably received by said framework in a manner permitting the descent of said bar under the influence of gravity; means for alternately upholding and releasing said clamping bar; an elongated member attached to said clamping bar in a manner whereby said elongated member moves upwardly and downwardly simultaneously with said bar; a clutching mechanism for grasping said elongated rod at times when said rod is in a downward position and releasing said rod at times when said rod is moving upwardly; other power actuated means attached to said clutching mechanism for exerting a downward force on said clutch and said clamping bar in addition to the force of gravity; and a spring in a position for cushioning the force exerted upon said clutch by said other power actuated means.

3. A paper cutting machine comprising a framework for supporting paper to be cut; a cutting blade slidably received by said framework; power actuated means attached to said cutting blade for causing said blade to define cutting movements; a clamping bar slidably received by said framework in a manner permitting the descent of said bar under the influence of gravity; means for alternately upholding and releasing said clamping bar; an elongated member attached to said clamping bar in a manner whereby said elongated member moves upwardly and downwardly simultaneously with said bar; a yoke adjacent to and overlapping the sides of said elongated member, said yoke being secured to said framework for preventing its excessive downward movement; a pair of lever-arms at opposite sides of said elongated member, said lever-arms being pivotally secured to said yoke at points between the respective ends of said lever-arm; means attached to said lever-arms on the sides of said pivot points respectively and adjacent said elongated member for transferring pressure from said lever-arms to said elongated

member; and other power actuated means for exerting pressure on said lever-arms, said other power actuated means being attached to each of said lever-arms on those respective sides of each of said pivot points which are opposite said elongated member.

4. A paper cutting machine comprising a framework for supporting paper to be cut; a cutting blade slidably received by said framework; power actuated means attached to said cutting blade for causing said blade to define cutting movements; a clamping bar slidably received by said framework in a manner permitting the descent of said bar under the influence of gravity; means for alternately upholding and releasing said clamping bar; an elongated member attached to said clamping bar in a manner whereby said elongated member moves upwardly and downwardly simultaneously with said bar; a yoke adjacent to and overlapping the sides of said elongated member, said yoke being secured to said framework for preventing its excessive downward movement; a pair of lever-arms at opposite sides of said elongated member, said lever-arms being pivotally secured to said yoke at points between the respective ends of said lever-arms; means attached to said lever-arms on the sides of said pivot points respectively and adjacent said elongated member for transferring pressure from said lever-arms to said elongated member; other power actuated means for exerting pressure on said lever-arms, said other power actuated means being attached to each of said lever-arms on those respective sides of each of said pivot points which are opposite said elongated member; and a spring in a position for cushioning the force exerted upon said lever-arms by said other power actuated means.

VICTOR Z. LYNNEQUEST.
